UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,294,425.

Specification of Letters Patent. Patented Feb. 18, 1919.

Application filed February 5, 1914. Serial No. 816,670.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 My invention relates to a computing machine, and is illustrated in connection with a combined typewriting and computing machine. Such machines usually include a gang of computing wheels forming a totalizer, and frequently include several such totalizers. The amounts to which these wheels are turned to compute are usually determined by type-operating numeral keys. In such machines it is often advantageous 20 to cause the numbers as they are written to be added or subtracted at will. For this purpose many devices have been used, many of which are cumbersome or awkwardly placed for the operator. According to my present 25 invention, controlling keys or levers for causing the computing wheels to add, subtract, or be neutral, are advantageously placed near the computing keyboard. For example, in a combined typewriting and 30 computing machine the said controlling levers for the computing wheels may be placed adjacent the typewriter keyboard, and where there are several such levers, there is preferably placed adjacent them a 35 post or alining finger rest which serves to indicate at which position the levers stand, and serves as a convenient guide for the fingers in positioning said lever. Where such a post is employed, the levers may be 40 readily placed by touch without requiring the attention of the eye of the operative.

My invention as herein disclosed is applied to a machine of the Underwood-Wright type, such as shown in my Patent 45 No. 1,020,082, dated March 12, 1912. Said patent shows a gang of computing wheels engaged *seriatim* by a master wheel in a manner determined by the typewriter carriage; said master wheel being power-driven, and the amount of turning at every actuation thereof being determined by the typewriter keys. In said patent there are shown key-controlled power-driven devices which drive the master wheel, and between

said devices and the master wheel is interposed a clutch which may be set so as to cause said master wheel to turn the computing wheels to add, subtract, or be neutral. Said clutch is held set in any position by a detent, and, according to my invention, 60 a lever for controlling said clutch may be placed just at the right of the Underwood typewriter keyboard, where it is convenient to the hand of the operative. This lever may control this clutch through a rock shaft 65 and pitman. Where there is more than one totalizer, any additional totalizer may be controlled through a controlling lever which, like the other lever, is adjacent the typewriter keyboard, which second lever may 70 be connected to a sleeve on said rock shaft, and from said sleeve may move the pitman connecting the appropriate clutch. In order to facilitate the setting of said levers by the operative, and to assist in recognizing 75 at a glance the points at which they stand, there may be advantageously placed near said levers a pillar or post which serves as a guide or rest for one finger of the operative, while another finger may be setting 80 this lever or levers.

Other features and advantages will appear hereinafter.

In the accompanying drawings,

Figure 1 is a perspective view of an 85 Underwood-Wright combined typewriting and computing machine, showing only so much of the machine as is convenient for the purpose of illustrating my invention as applied thereto.

Fig. 2 is a sectional side view showing the controlling levers and some adjacent parts.

In the Underwood-Wright machine, the usual typewriter platen carriage 1 carries a work-sheet (not shown herein) on which 95 type (also not shown herein) are caused to print by numeral keys 2 and alphabet keys 3. As said keys thus print, they cause the typewriter carriage 1 to be fed along a letter-space at every operation of a key. 100 As the typewriter carriage travels along, it carries with it by an arm 4, a computing machine carriage 5 on which is adjustably mounted a totalizer 6 comprising dial wheels 7. Said totalizer is thus conveniently placed 105 for the eye of the operative.

When in the adding zone, one of said dial wheels 7 may be turned at every operation

of a numeral key 2, the mechanism for this purpose including the usual power-driven master wheel 8, said master wheel comprising teeth 9 which in the adding zone engage 5 in the usual manner with internal teeth on computing wheels (not shown herein) mounted in the totalizer 6. Said master wheel is fast on the usual shaft 10, said shaft being connected through a clutch 11 of the usual kind to the usual drive shaft 12 of the Underwood-Wright combined typewriting and computing machine.

The clutch 11 is of the usual kind employed in such machines and includes a bevel gear 13 fast on the master wheel shaft 10, said gear constantly meshing with two bevel gears 14 and 15 which run loosely on the shaft 12, but either of which may be seized thereto by a seizing member 16 slideably 15 splined on the shaft 12 and provided at each end with teeth 17 which mesh with similar teeth on each of the bevel gears 14 and 15. Said seizing member 16 may also occupy an intermediate position in which its 20 teeth 17 fail to mesh with either of the bevel gears 14 or 15, so that the clutch 11 may be said to occupy a neutral position, because at this time the drive shaft 12 has 25 no effect on the master wheel whichever way 30 it may turn.

When, however, the seizing member 16 engages one of the bevel gears 14 or 15, it will cause the dial wheels 7 to turn in adding direction, while when it engages the 35 other, it will cause said wheels to turn in subtracting direction.

The machine as shown herein also includes the usual carry-over assisting roll 18 fast on its shaft 19, said carry-over assisting 40 roll, like the master wheel, being power-driven. The carry-over shaft 19 is thus driven by a drive shaft 20 which, like the shaft 12, is always turned in one direction. In order to permit the carry-over shaft 19 45 to be reversed or be neutral whenever the master wheel shaft 10 is reversed or neutral, there is provided between the drive shaft 20 and the carry-over shaft 19 a clutch 21 like the clutch 11.

Said clutch 21 includes bevel gears 22 and 50 23 which are loose on the drive shaft 20 but are adapted to be clutched thereto by a clutching member 24 like the clutching member 16, and said gears when so clutched thereto, like the bevel gears 14 and 15, turn the carry-over shaft 19 in one direction or the other by a bevel gear (not shown herein) with which they are constantly in mesh. Said clutching member 24 may also occupy 55 an intermediate position whenever the clutching member 16 occupies an intermediate position.

For causing the two clutches to be shifted together, there is provided a lever 25 60 pivoted between its ends at 26, which lever

carries at each end a pin 27 lying in a groove 28 in each of the clutching members 16 and 24. In order to allow for lost motion in case of any imperfect meshing of the teeth on the seizing member 24 with 70 the internal teeth on its bevel gears 22 and 23, the lever 25 is formed of two parts connected together by a yielding spring 29. The smaller part 30 of said lever, which part engages with the clutching member 24, 75 is formed of an arm pivoted on the lever 25 at 31 and includes an arm 32, which arm is engaged by the yielding spring 29, said spring always moving with the lever 25 because it is firmly mounted in a pin 33 on 80 the said lever, which pin forms a pivot on which the smaller member 30 is pivoted.

In order to prevent too much motion by the yielding of the spring 29, the smaller part 30 includes arms 34 which extend on 85 either side of the head 35 of the pivot 26 on which the lever 25 is pivoted. The lever 25 is detained in whatever position it holds the clutches by a spring detent 36, which detent, according to the position of the lever 25, engages one of three notches in an upwardly extending arm 37 of the lever 25.

According to my invention, the lever 25 is provided with a dependent pitman or link 38 for moving it, said link being controlled 90 by a lever 39 adjacent the right-hand side of the typewriter keyboard which comprises the alphabet and numeral keys 3 and 2. The lever 39 is fast to a rock shaft 40, which shaft carries at its outer end a disk 41, to 100 which disk the pitman 38 is pivoted.

The lever 39 by which the rock shaft 40 is turned includes a finger piece 42 and a body 43, said body being formed as the blade or plate to which the finger piece 42 105 is joined by a bent portion. The body 42 of the lever 39 is extended down beyond the rock shaft 40 forming a broad plate portion 44, the edge of the portion 44 being cut into three notches 45, 46, 47, which notches 110 coöperate with a spring detent wheel 48, said detent wheel being adapted to hold the lever 39 in any position in which it is set. The detent wheel 48 is loosely pivoted on a freely swinging detent arm 49, which arm 115 is drawn up by a spring 50 to hold the wheel 48 engaged with any of the notches 45, 46, 47.

The lever 39 is held against overthrow by the flat sides 51 of the end notches 45 120 and 47, which are extended downward so that they bear flat against the wheel 48 when said wheel is engaged with an end notch, and said end notches are therefore unable to cam said wheel downward. The wheel 125 48 is cammed downwardly by the slanting sides of the notches 45, 46, 47, whereby the lever 39 is set to a new position; the notches for this purpose being fairly shallow.

The Underwood-Wright combined type- 130

writing and computing machine frequently has a second totalizer 52 which is associated with a second totalizer carriage 53, said second totalizer carriage including a second master wheel 54, and being connected intermittently to the typewriter carriage 1 independently of the first totalizer carriage 5, said connection including a rearwardly extending lever 55 and other devices not specifically material in the present invention, which are set forth in the patent to Walter Wright, No. 1,244,398, dated October 23, 1917. The said second master wheel 54 is shown driven by the same drive shaft 12 as the first-named master wheel 8 and is connected to drive its master wheel 54 in either direction by the second master wheel shaft 56, said second master wheel shaft being connected to the drive shaft 12 by a clutch 57 which includes a lever identical with the lever 25 and having identical functions, so that a description of the clutch 57 is unnecessary. The said lever 58 also shifts the clutch 59 between the drive shaft 20 and the carry-over assisting shaft 60. This clutch 59 corresponds in every respect to the carry-over clutch 21, and so need not be described at length.

The lever 58 is provided with notches 61 like the notches in 37 to coöperate with a detent 62 to hold the clutch positioned in whatever plate it is set. The lever 61 is shiftable to move the clutch 60 to adding, subtracting and neutral positions by the dependent link or pitman 63 which corresponds to the pitman 38; said link 63 being connected to a controlling lever 64, which corresponds to the lever 39 in all respects, except that it controls the totalizer 52. The lever 64 is connected to the pitman 63 by the sleeve 6 journaled on the rock shaft 40, said sleeve having on its outer end a disk 66 to which the pitman 63 is attached. The said sleeve 65 is journaled in the fixed bar 67 of the frame of the combined machine and is held against sliding on said fixed bar by a collar 68 fast on said sleeve and lying on the opposite side of the side bar 67 from the disk 66. The shaft 40 is journaled in the side 69 of the typewriting machine. The lever 64 which controls the second totalizer 52 includes a finger piece 70 formed like the finger piece 42, as an extension of the plate 71, said plate including notches 72, 73, 74, which notches coöperate with a spring detent wheel 75. Said wheel 75 like the wheel 48, is loose on the lever 76, which is driven upward by a spring 77 to hold the wheels 75 in position, and the end notches 72 and 74 are provided with flat portion 78 to prevent overthrow of the lever 64. The levers 39 and 64 work in slots 79 and 80 in the casing, and the sides of said slots prevent the shaft 40 and sleeve 65 from sliding. Said casing also

covers the detents 48 and 75, and the arms carrying said detents are journaled on a shaft 82 and held in place by collars 83. Said casing is attached to the side frame 69 of the typewriter adjacent the lower bank 70 of the typewriter casing.

Also said casing is provided with a finger post 81 which projects upward from its surface so that the levers 39 and 64 will be beside or alined with the post 81 when said levers hold their clutches in neutral position. Said post therefore forms a convenient guide against which the operative may pinch her fingers together to almost subconsciously position the controlling levers 39 80 and 64 to their neutral positions. Also by resting one finger or thumb on the finger post 81, the operative can conveniently and without looking accurately position either of the levers 34 and 69 to either adding or 85 subtracting position.

The casing in which the levers work is marked adjacent the slots with legends describing the functions of the lever in each slot. In the example shown, the left-hand lever is marked "Column", meaning it controls the column adder or totalizer, and the right-hand lever is marked "Cross", because it controls the totalizer used for cross-adding.

Variations may be resorted to within the scope of the invention, and portions of the improvements may be used without others.

Having thus described my invention, I claim:

1. In a combined typewriting and computing machine, the combination with typewriting mechanism having a keyboard, of computing mechanism including a plurality of computing heads, a state controlling mechanism adjacent the typewriter keyboard for controlling the states of said computing heads, as to addition, subtraction or neutral, and means for determining by the sense of touch the positions of said state controlling mechanism to produce any combinations of said states of said computing heads. 100
2. In a combined typewriting and computing machine, the combination with a computing head, of state controlling mechanism including a lever adjacent the typewriter keyboard for controlling the state of said computing head as to addition, subtraction or neutral, and a guide post adjacent said lever, said lever and guide post adapted to be engaged between the fingers of the operative to position by touch said controlling mechanism so as to produce any of said states of said computing head. 115
3. In a combined typewriting and computing machine, the combination with typewriting mechanism including a keyboard, of computing mechanism including a plurality of computing heads, state controlling mech- 125

anism including a plurality of levers adjacent the typewriter keyboard for controlling the states of said computing heads as to addition, subtraction or neutral, and a single guide post for both said levers, said guide post and said levers being adapted to be engaged between the fingers of the operative to position said levers by touch, to control any combinations of states of said computing heads.

4. In a combined typewriting and computing machine, the combination with typewriting mechanism including a keyboard, of a plurality of computing heads, state controlling mechanism including a plurality of levers adjacent the typewriter keyboard for controlling the states of said computing heads as to addition, subtraction or neutral, a plurality of levers, and a single guide post for both said levers, said guide post being between said levers, and said guide post and said levers being adapted to be engaged between the fingers of the operative to position said levers by touch, to control any combinations of states of said computing heads.

5. In a combined typewriting and computing machine, the combination with typewriting mechanism including a keyboard, of computing mechanism including a computing head, a guide post adjacent said keyboard, a lever pivoted adjacent said guide post and having a plate forming part thereof, said plate having notches therein corresponding to different states of said computing head, the end notches of said plate having projecting portions, and means coöperating with said notches, said means and said guide post coöperating to locate said lever in position to control one state of said computing head, and said means and said projecting portions coöperating to locate said lever in position to control another state of said computing head.

6. In a typewriting machine, the combination with a frame and computing devices, of a keyboard having keys controlling said computing devices, means at one side of said frame for determining how said keys shall so control said devices, levers adjacent said keyboard for controlling said determining means, a pitman between each determining means and its lever, and rotatable devices

one on each lever for connecting it to its pitman.

7. In a combined typewriting and computing machine, the combination with computing devices and a reversing clutch for each computing device, of a touch locating means for controlling the clutches, said means including a detent for each clutch for holding it in position, a lever for each clutch for shifting it, and a detent for each lever.

8. In a combined typewriting and computing machine, the combination with typewriter keys forming a keyboard, of computing devices, a lever adjacent said keyboard for controlling one computing device, another lever adjacent said keyboard controlling another computing device, a shaft on which one lever is mounted, and a sleeve on said shaft on which the other lever is mounted.

9. In a combined typewriting and computing machine, the combination with a column totalizer and a cross totalizer, of typewriter keys forming a keyboard, a lever for each totalizer adjacent said keyboard to determine the state of each totalizer independently, and means for both selecting and positioning each of said levers by the sense of touch.

10. In a combined typewriting and computing machine, the combination with a computing head, of typewriting mechanism including a keyboard, state controlling mechanism adjacent the typewriter keyboard for controlling the state of said computing head as to addition, subtraction or neutral, and means for determining by the sense of touch, the position of said controlling mechanism to produce any of said states of said computing head.

11. The combination with a plurality of totalizers, of individual controlling mechanisms, for said totalizers, a shifting lever connected to operate each of said controlling mechanisms, said shifting levers being arranged side by side, and a handrest located at the point of intersection of lines drawn from the extreme opposite positions of said levers to each other, said rest acting as a guide for the hand in shifting said levers.

GUSTAVE O. DEGENER.
